United States Patent Office

Des. 195,606
Patented July 2, 1963

195,606

COMBINED TRANSPARENT AND OPAQUE PROJECTOR

James O. Kuhn, Cincinnati, Ohio, assignor to Kenner
Products Company, Cincinnati, Ohio, a corporation of
Delaware

Filed Oct. 12, 1962, Ser. No. 72,090

Term of patent 14 years

(Cl. D61—1)

FIGURE 1 is a side elevational view of a combined transparent and opaque projector showing my new design.
FIGURE 2 is an elevational view of the front thereof.
FIGURE 3 is an elevational view of the back thereof.
FIGURE 4 is a top plan view thereof.

I claim:

The ornamental design for a combined transparent and opaque projector, substantially as shown.
